CLAIM

The ornamental design for an orthotic device, as shown and described.

DESCRIPTION

FIG. 1 is a perspective view of one embodiment of an orthotic device according to the disclosure.

FIG. 2 is an end view of the orthotic device of FIG. 2.

FIG. 3 is a front view of the orthotic device of FIG. 2.

FIG. 4 is a rear view of the orthotic device of FIG. 2.

FIG. 5 is a top view of the orthotic device of FIG. 2.

FIG. 6 is a perspective view of another embodiment of an orthotic device according to the disclosure.

FIG. 7 is an end view of the orthotic device of FIG. 6.

FIG. 8 is a front view of the orthotic device of FIG. 6.

FIG. 9 is a rear view of the orthotic device of FIG. 6; and, FIG. 10 is a top view of the orthotic device of FIG. 6.

The dash-dot broken lines in FIGS. 1, 3-5, 6 and 8-10 immediately adjacent to claimed surfaces represent the boundaries of the claimed design and also show portions of the orthotic device that form no part of the claimed design. The dash-dot broken lines in FIGS. 1-10 show portions of the orthotic device and form no part of the claimed design. None of the broken lines shown in the figures forms any part of the claimed design.

The orthotic device is shown with a symbolic break in its length. The appearance of any portion of the article between the break lines forms no part of the claimed design.
